UNITED STATES PATENT OFFICE.

L. B. CHOC PERKINS AND RAY H. DOBBINS, OF OKLAHOMA CITY, OKLAHOMA.

TITLE LOCK.

Application filed September 24, 1926. Serial No. 137,526.

This invention aims to provide novel means whereby tile may be held against a wall, jamb, frame or other structural elements.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

In the drawings:—

20 Figure 1 shows in perspective, a device constructed in accordance with the invention;

Figure 2 is a perspective view wherein the article is shown in use as a means for 25 connecting tile to a brick wall;

Figure 3 is a perspective view wherein the device is shown as a means for holding tile upon a door frame; and

Figure 4 is a view wherein the article appears in use as a means for binding a wall 30 of brick or tile to a window frame.

The device forming the subject matter of this application comprises a strip 1 of bendable metal, one end portion 2 of which is supplied with transverse corrugations 3, the other end portion 4 of which is supplied with longitudinal corrugations 5, the corrugations 3 and 5 covering the entire surface of the strip 1. In the end portions 2 and 4 of the strip 1 there are openings 6 which afford a mortar clinch. Along their longitudinal edges, the end portions 2 and 4 of the strip 1 are supplied with perforations 7.

The strip 1 may be laid between tile 8 in 45 a wall, to anchor the tile to a wall of brick 9, or other structural elements, one end of the strip 1 being placed upon the tile 8, and the other end of the strip overlapping the wall made out of the members 9. If desired, the 50 strip 1 may be bent transversely as at 10, to form rectangularly disposed wings 11 and

12, as in Figure 3, the wings 11 being held on the lintel 14 of a doorway, or upon the stiles 15 thereof, by securing elements inserted through the perforations 7, the wing 55 12 entering between the tiles 16 in the wall. The strip 1, having been nailed at one end to the door frame, may be bent into any desired shape, at the other end, as Figure 3 will show. In Figure 4, the wing 11 is nailed at 60 17 to a window frame 18, and the wing 12 overlaps and lies between bricks 19 or other structural elements in the wall.

What is claimed is:—

1. In a device of the class described, a 65 strip provided at one end with transverse corrugations, and at its other end with longitudinal corrugations, the longitudinal and transverse corrugations covering substantially the entire area of the strip, the longitudinal corrugations affording a mortar hold against transverse slipping, and the transverse corrugations affording a mortar hold against longitudinal slipping and also permitting the strip to be bent at the innermost transverse corrugation and at the inner 70 end of the longitudinal corrugations, to form angularly disposed wings. 75

2. In a device of the class described, a strip provided at one end with longitudinal 80 corrugations, and at the other end with transverse corrugations, all of the corrugations being of substantially the same height, each end portion of the strip being supplied with openings of sufficient size to afford a 85 mortar clinch, the strip being supplied along its longitudinal edges, with perforations of such size as to receive securing elements.

3. In a device of the class described, a strip provided at one end with longitudinal 90 corrugations, and at the other end with transverse corrugations, all of the corrugations being of substantially the same height, each end portion of the strip being supplied with openings of sufficient size to afford a 95 mortar clinch.

In testimony that we claim the foregoing as our own, we have hereto affixed our signatures.

L. B. CHOC PERKINS.
RAY H. DOBBINS.
